FOUNDRIES, OF CHICAGO, ILLINOIS, A CORPORATION OF NEW JERSEY.

BRAKE-HANGER EQUIPMENT.

1,323,310.

Specification of Letters Patent. Patented Dec. 2, 1919.

Application filed June 27, 1918. Serial No. 242,135.

To all whom it may concern:

Be it known that I, ERIC W. PALMQUIST, a citizen of the United States, residing at Chicago, in the county of Cook and State of Illinois, have invented certain new and useful Improvements in Brake-Hanger Equipment, of which the following is a specification.

This invention relates to brake hanger equipments.

The object of this invention is to provide a simple, inexpensive and durable brake hanger equipment wherein the hanger may be readily applied to its support, moved into a locking position with respect thereto, and readily removed therefrom.

The invention is illustrated on the accompanying sheet of drawings, in which—

Figure 1 is a fragmentary side elevation 20 of a railway car truck embodying my invention;

Fig. 2 is a sectional view taken through the car truck and showing the manner of applying the brake hanger to its support, 25 also showing the novel supporting member; and,

Fig. 3 is a fragmentary plan view of the arrangement shown in Fig. 2.

The truck side frame 10 is provided with 30 a laterally extending support 11, in which a brake hanger 12 is mounted, the lower end of the brake hanger being connected to a brake head 13 carrying a brake shoe 14 arranged to coöperate with an associated truck wheel 15.

The outer end of the bracket or support 11 is provided with spaced upper and lower jaw members 16 and 17, at the rear end of which is provided a transversely extending horizontal bearing portion 18 for the reception of the upper portion 19 of the closed loop hanger 12. The jaws 16 and 17 proper are skewed into a position wherein the same are arranged at substantially an angle of 45° with respect to the bearing portion 18, or with respect to the horizontal and extend entirely across the jaw portion of the support in the same direction. These spaced and skewed jaws 16 and 17 thereby 45 form an opening therebetween, which also is at an angle with respect to the bearing portion 18. It is apparent, therefore, that in order to apply the link hanger, the latter must be moved into an angular position so 50 that its upper portion 19 coincides with the angle of the skewed jaws, whereupon said

portion 19 may slide through the opening between the jaws and downwardly through said opening into the horizontally arranged bearing portion 18. In order to 60 withdraw the link brake hanger it is necessary for it to take a reverse movement. However, when the link is applied to the brake head behind the brake shoe, it is impossible for the hanger to move into an angular position permitting the removal of 65 the hanger. Accordingly, when the hanger is in the position shown in the figures of the drawings, it is locked, thereby preventing the hanger from becoming disengaged from 70 its support and thereby preventing the hanger, brake beam, head and shoe from falling to the track and causing a wreck.

It is a simple matter to apply this hanger, it not being necessary to remove the wheels 75 from the truck. It is simply necessary to turn the hanger 12 at an angle while still maintaining it in a vertical plane intermediate the truck side frame bolster leg and the wheel, whereupon the upper portion 19 80 of the hanger will be received between the skewed jaw members 16 and 17 and set into place in the bearing portion 18.

It is my intention to cover all modifications of the invention falling within the 85 spirit and scope of the following claims.

I claim:

1. In brake mechanism, the combination of a support having skewed jaws extending entirely across the jaw portion of said support in the same direction, and a hanger applied to said support between said skewed jaws.

2. In brake mechanism, the combination of a support having a bearing portion and 95 skewed jaws arranged at an angle with respect thereto, and extending entirely across the jaw portion of said support in the same direction, and a brake hanger which may be passed between said skewed jaws into said bearing portion wherein the hanger is locked.

3. In brake mechanism, a truck side frame having a supporting portion with a bearing therein and skewed jaws, which extend in the same direction throughout their length, 105 and a brake hanger insertible between said jaws and normally located in said bearing portion.

Signed at Chicago, Illinois, this 19 day of June, 1919.

ERIC W. PALMQUIST.
